UNITED STATES PATENT OFFICE.

PETER ZUMBERG AND JOSEPH SARDIN, OF DETROIT, MICHIGAN.

OIL-PRESS.

1,277,677.

Specification of Letters Patent.

Patented Sept. 3, 1918.

Application filed April 18, 1918. Serial No. 229,232.

To all whom it may concern:

Be it known that we, PETER ZUMBERG and JOSEPH SARDIN, citizens of the United States and Russia, respectively, residing at Detroit, 5 county of Wayne, State of Michigan, have invented a certain new and useful Improvement 10 in Oil-Presses, and declare the following to be a full, clear, and exact description of the same, such as will enable others skilled in the art to which it pertains to make and use the same, reference being had to the accompanying drawings, which form a part of this specification.

Our invention relates to presses and an 15 object of our improvements is to provide an improved apparatus for pressing the oil from various kinds of seed.

We secure this object in the device illustrated in the accompanying drawings in 20 which;

Figure 1 is an elevation, partly in section, of an apparatus embodying our invention.

Fig. 2 is a plan view of the same.

Fig. 3 is a detail plan view, partly in 25 section, on the line C—C Fig. 1.

Fig. 4 is a detail section on the line D—D

Fig. 1.

Fig. 5 is a detail section showing the construction of the hydraulic cylinder and ram 30 and the carrying plate on the latter.

Fig. 6 is an elevation of the outer envelop of the container for the seed to be pressed.

Fig. 7 is the inner envelop of the same.

Fig. 8 is a tank for containing liquid, b b are 35 cylinders having pistons operating therein and connecting rods pivoted to cranks on a crank shaft a³ resting in bearings on standards in the tank a, a² is a pulley by which 40 the crank shaft a³ may be rotated.

We have represented the cylinders of the pumps generally without illustrating the valves operative therewith inasmuch as these are conventional constructions and 45 can easily be supplied by a mechanic. c is a common delivery pipe for the cylinders b b, and d is a valve in the pipe c adapted to be opened to put the interior of said pipe into communication with the interior of the 50 tank a. e is a lever by which the valve d may be opened.

g is a hydraulic cylinder having a plunger h therein. The pipe c is provided with a pressure gage between the pump and the 55 hydraulic cylinder as shown. The delivery pipe c opens into the cylinder g below the

plunger h. m is a carrying plate on the upper end of the plunger h. i is the base plate and j an upper plate united by guide bars k k to form a frame. The hydraulic cylinder g is secured to the base plate i of said frame and opens therethrough. m is a carrier plate normally resting upon the base plate i of the frame and secured to the upper end of the plunger h. n is a cylindrical projection extending downward from the center of the plate j. The projection n is axially in line with the plunger h. p and p² are symmetrical halves of a cylinder p. These halves are provided with lugs p³ extending outward forming adjacent edges and having registering cylindrical openings therein. p⁴ are vertical slots through the walls of the cylinder p. q q² are the two symmetrical halves of an outer envelop 75 cylinder having lugs q⁴ upon two adjacent edges which are adapted to be secured together by bolts and nuts. There are registering lugs q⁵ at the other adjacent edges of the parts q q² and these parts are cut 80 away to form openings having parallel horizontal walls as shown at q⁵ in Fig. 6.

The container for the seed is formed by putting two halves of the cylinder p together, putting the outer envelop q around 85 the cylinder p and passing a pin or bolt x through the registering openings of the lugs q³ and p³. The latter of which lugs are interposed between the lugs q⁵ in the openings q⁵. The lugs q⁴ are then secured together 90 by bolts and nuts.

The seed container thus formed is placed upon the carrier plate m, as shown in Fig. 1, the seed placed within the hollow of the inner cylinder p and the hydraulic pumps 95 are set in operation forcing the plunger h upward carrying the carrier plate m and compressing the seed by means of the projection n passing into the cylinder p, the oil running out through slots p⁴ in the latter cylinder and passing through the openings q⁵ falling upon the carrier plate m which is hollowed out at its outer surface and running off in a spout m².

What we claim is:

1. In an oil press, the combination of an inner envelop having vertically extending slots through its wall, an outer envelop having horizontal openings through its walls, and means for securing said outer envelop around said inner envelop.
2. In an oil press, the combination of an

inner envelop formed in two halves and having vertical slots through its walls, an outer envelop formed in two halves having horizontal openings in its walls, the outer envelop being adapted to have its two parts rigidly secured together around said inner envelop.

3. In an oil press, the combination of an inner envelop having two parts having lugs 10 with registering apertures therethrough at adjacent edges and having vertical slots through its walls, an outer envelop having lugs with registering apertures at adjacent

edges and having horizontal openings in its walls, said outer envelop being adapted to 15 pass around said inner envelop with the apertures through its lugs registering with the apertures through the lugs of the inner envelop, a bolt passing through the apertures in said lugs, and means for securing 20 the edges of the outer envelop opposite said lugs rigidly together.

In testimony whereof we sign this specification.

PETER ZUMBERG.
JOSEPH SARDIN.

Copies of this patent may be obtained for five cents each, by addressing the "Commissioner of Patents, Washington, D. C."
